CONTACT DEVICE FOR ELECTRIC MASTER CLOCKS

Ferdinand Schneider, Fulda, Germany

Application December 28, 1935, Serial No. 56,457

3 Claims. (CL 200—26)

This invention relates to contact-devices for electric master-clocks which serve for operating secondary electric clocks. In heretofore known contact-devices used for this purpose current-carrying contact-springs have been used, said contact-springs carrying the operating current for the secondary clocks. These known contact-devices have the disadvantage that they do not permit passage of a relatively strong operating current so that only a small number of secondary clocks can be operated from the master-clock. Furthermore, known contact-devices are liable to relax after some time, that is the contact-members will lose their tension, and in consequence thereof the contact-pressure will soon be diminished with the result that a safe and reliable making of the contacts cannot be attained with certainty for a greater length of time.

According to this invention, the aforementioned current-carrying contact-springs are replaced by contact-levers which are amply dimensioned in cross-section, said contact-levers co-operating with contact-pins alternately brought into efficient sliding contact therewith. In order to attain a reliable and intimate contact, the free contact-levers are pivotally mounted at one of their ends, while the other of their ends are connected with each other by means of a tension-spring keeping together both contact-levers. Moreover, all of said contact-levers are properly supported in such a manner that one contact-lever is being firmly pressed against its companion contact-member, in the present case a contact-bar, whenever and as long as the other contact-lever is in sliding contact with its companion contact-member, that is in the present case a contact-pin on a contact-disk. In consequence of this improvement in the making of the contact, the contact-resistances will practically be reduced to nil, so that the electric circuit associated with the contact will be able to operate a greater number of secondary clocks than had heretofore been possible. In addition to the aforementioned contact-levers which serve for the making of the main contacts, there are further provided two auxiliary contact-levers in parallel to the former, said auxiliary levers serving to suppress the formation of sparks at the main contacts. These auxiliary contact-levers are likewise operated by a common tension-spring under most reliable conditions with respect to making the contacts for the spark-extinguishing circuit. As the main and auxiliary contact-levers never change their contact position, these contact-organs will warrant a permanently reliable op-

eration of secondary clocks from a master-clock.

In the accompanying drawing I have represented two examples of construction of my novel contact-device for electric master-clocks, Fig. 1 being a front-view of a contact-device including main contacts, spark-extinguishing contacts, and the electric circuits operated by said contacts, Fig. 2 a section along line A—B of Fig. 1, Fig. 3 a front-view of my novel contact-device without a spark-extinguishing circuit, the device being shown in condition of rest, and Fig. 4 the contact-device shown in Fig. 3 in condition of making contact.

In the construction of the contact-device shown in Figs. 1 and 2, the clockwork of the master-clock is provided with an arbor 4 rotated at a constant speed by the clockwork and has an insulating plate 2 mounted on plate 1 by means of screws 3. On an extension of the arbor 4 passing through the plate 1, there is mounted an insulating tube 5 carrying the contact-disk 6. On the latter is mounted a contact-pin 7 and on either side thereof an insulated pin 8 and 9. To the plate 1 of the clockwork there is further fastened an insulating bushing 10, a contact-bolt 11 being mounted in said bushing. The bolt 11 forms the carrier of a sliding-spring 12, the free end of said spring sliding on the periphery of a contact-disk 6 in full contact therewith. The insulating plate 2 further carries the binding-posts or terminals 13, 14, 15, 16 and 17, the contact-levers 22, 23, 24 and 25 being pivotally mounted on said binding-posts or terminals by means of set screws 18, 19, 21 and 20, respectively. The terminal 15 extends in upward direction into a current-bar 26, which carries at its upper end a contact-member preferably in the form of a silver-plate 27. The contact-levers 22, 23, 24 and 25 are re-inforced at their inner surfaces by means of silver-straps 22a, 23a, 24a and 25a and more particularly at those surfaces at which they come in contact with the contact-pin 7 serving for establishing the electric circuit for the operation of the secondary clocks. The auxiliary contact-levers 22 and 25 are arranged in front of said main contact-levers 23 and 24 at some distance therefrom and parallel thereto. Swinging motion of said auxiliary contact-levers is limited in inward direction by fixed stops 28 and 29 on the insulating plate 2. At the height of the contact-disk 6 the inner distance between said two auxiliary contact-levers 22 and 25 is somewhat smaller than that between the main contact-levers 23 and 24. From the contact-bolt 11 leads a connection 30 to the negative pole of 55

the battery 31, the positive pole of the latter being connected by a lead 32 with the terminal 15. The connections 33 and 34 leading to the secondary clocks to be operated by the master-clock are connected to the terminals 14 and 16, respectively. From the lead 33 is branched off a lead 36 connected to one terminal of a coherer-resistance 37, while the other terminal of the latter is connected to the terminal 13 by means of the lead 38. The lead 34 is connected by the lead 39 with the one terminal of a second coherer-resistance 40, the other terminal of the latter being connected to the terminal 17 by the lead 41. At the head-end of the main contact-levers 23 and 24 are provided insulating rollers 42 and 43 to which a tension-spring 44 is fastened, said tension-spring keeping together said two main contact-levers at this place. In like manner, insulating rollers 45 and 46 are provided at the head ends of said auxiliary contact-levers 22 and 25, said insulating rollers serving as anchorages for the ends of the tension-spring 47.

The construction shown in Figs. 3 and 4 differs from that shown in Figs. 1 and 2 solely therein that the auxiliary contact-levers 22—25, as well as the coherer-resistances 37 and 40, which are used as additional organs for spark-extinguishing, are omitted.

The operation of the abovedescribed device is described in the following, the main contacts according to Figs. 3 and 4 being described in inoperative condition. All parts of the contact-device are in the position shown in Fig. 3. Upon rotation of the contact-disk 6 in direction of the arrow, first the insulating pin 8 on said disk will abut against the contact-lever 23 and press the latter away from its position of rest on the contact-member 27. Upon continued rotation of said disk 6 the contact-pin 7 thereon will come in conductive connection with the contact-lever 23 as shown in Fig. 4, thereby establishing an electric circuit 31, 30, 11, 12, 6, 7, 23, 14, 33, 35, 34, 16, 24, 27, 26, 15, 32, the secondary clocks being now moved forward one minute. This making of the contact according to this invention takes place without resistance which is due, on the one hand, to the greater tension of the spring 44 firmly pressing the contact-lever 24 against the front surface of the contact-member 27, and on the other hand, to the sliding of the contact-pin 7 in full contact along the contact-lever 23. Upon further continued rotation of the contact-disk 6, now the insulating pin 8 abuts against the contact-lever 23, causing the contact-lever 23 to return into its inoperative position onto the contact-member 27, somewhat subsequently to the interruption of the contact between the pin 7 and the contact-lever 23. Subsequent contact between the pin 7 and the contact-lever 24 is effected in like manner to cause change of direction of the current supplied to the secondary clocks. In order to suppress sparking at the contact, the contact-device is constructed as shown in Figs. 1 and 2. In this construction of the contact-device the coherer-resistance 37 is connected across the terminals of the auxiliary contact 13 and of the main contact 14 by way of the leads 36 and 38, while the coherer-resistance 40 is connected across the terminals of the auxiliary contact 17 and of the main contact 16 by way of the leads 39 and 41. Prior to the position of operation, according to Fig. 4 which shows a construction of the contact-device without spark-extinguishing means, the auxiliary contact-lever

22 which abuts against the pin 28 had been gripped by the contact-pin 7 and moved away from said pin 28. By this an electric circuit is at first preliminarily established by way of the coherer-resistance 37 and after some time the 5 contact-pin 7 abuts against the main contact-lever 23 to fully establish the electric circuit. During the operation of contacting both contact-levers 22 and 23 will be in contact with the pin 7. Upon further rotation of the contact-disk 6 the main contact-lever 23 will come out of contact with the pin 7 and first interrupt the circuit. The electric circuit, however, still remains closed by way of the coherer-resistance 37 and somewhat later the circuit is fully interrupted, when the contact-pin 7 comes out of contact with the auxiliary contact-lever 22. During the subsequent operation, the connection is made in like manner by way of the other two contact-levers 24 and 25 in cooperation with the coherer-resistance 40. Owing to the employment of rigid contact-levers which are operating resiliently one against the other, there will be secured a proper and uniform operating motion of the contact-device, with the result that in the 25 constructions shown in Figs. 1 and 2 sparking will be efficiently suppressed at the contacts and the latter remain free of the formation of oxide.

I claim:

1. A switch mechanism for electric master-clocks comprising, a disk having a conducting surface and rotated at constant speed, means to connect the conducting surface of said disk to a source of current, a pair of rigid contact arms pivotally mounted adjacent said disk, one upon each side of the axis thereof, a pin secured to said disk in conducting relationship with the conducting surface thereof and engageable alternately with said contact arms, a tension spring having its ends secured to but insulated from the free ends of said arms and operable to swing said arms toward the axis of said disk, and a fixed contact element arranged alternately to make electrical contact with said contact arms and form a stop for limiting the swinging movement 45 of said arms toward the axis of said disk.

2. In a switch mechanism for master-clocks, the combination of a disk rotated at a constant speed, means to connect one terminal of a source of current to said disk, a fixed contact, means to connect said fixed contact to the other terminal of the source, a pair of pivotally mounted rigid-contact arms, a single spring for swinging said arms toward one another and into engagement with said fixed contact, and means on said disk alternately engageable with said arms to move said arms away from said fixed contact against the tension of said spring and thereafter to make an electrical contact with the arm.

3. In a switch mechanism for master-clocks of 60 electrical clock systems, the combination of a fixed contact, a pair of pivotally mounted rigid contact arms, resilient means to force said arms into contact with said fixed contact, and means operable alternately to move said arms from contact with said fixed contact, said means comprising insulating means for engaging said arms while they are in close proximity to said fixed contact, and conducting means for completing electrical circuits through said arms after the latter have been moved from contact with said fixed contact.
